(57) CLAIM

The ornamental design for an outsole of a shoe, as shown and described.

DESCRIPTION

FIG. 1 is a perspective view of the outsole of a shoe showing my new design; and,

FIG. 2 is a plan view of the outsole of a shoe shown in FIG.

The phantom lines representing a shoe upper and midsole shown in FIGS. 1-2 are for illustrative purposes only and form no part of the claimed design.

The heavy black outline is understood to represent a boundary between claimed and unclaimed subject matter.
